CLAIM

The ornamental design for a pair of earphones, as shown and described.

DESCRIPTION

FIG. 1 is a front elevational view of a pair of earphones, showing the new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

1 Claim, 5 Drawing Sheets
